CLAIM

The ornamental design for a semiconductor light emitting module, as shown and described.

DESCRIPTION

FIG. 1 is a front view of a semiconductor light emitting module showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines shown in the drawings represent portions of the semiconductor light emitting module that form no part of the claimed design.
